UNITED STATES PATENT OFFICE.

CLARE WEST, OF LOS ANGELES, CALIFORNIA, ASSIGNOR TO CECIL B. DE MILLE, OF LOS ANGELES, CALIFORNIA.

DESIGN FOR A CLOAK.

59,571.

Specification for Design.

Patented Nov. 1, 1921.

Application filed January 31, 1921. Serial No. 441,434. Term of patent 7 years.

To all whom it may concern:

Be it known that I, CLARE WEST, a citizen of the United States, residing at Los Angeles, in the county of Los Angeles, State of California, have invented a new, original, and ornamental Design for a Cloak, of which the following is a specification, reference being had to the accompanying drawing, forming part thereof.

Figure 1 is a front view of the cloak with arms extended; Fig. 2 is a rear view of the cloak with the arms extended, and Fig. 3 is a three quarters front view of the cloak with the arms to the sides.

I claim:

The ornamental design for a cloak, as shown.

CLARE WEST.

Witnesses:

JOB H. FISHER,

FERN FROST.
